DANCER'S BIRD TAIL DEVICE

George Edward Golden, New York, N. Y.

Application January 31, 1941, Serial No. 376,847

16 Claims. (CL. 272—21)

This invention relates to a device adapted to be worn by a dancer for simulating, in both appearance and action, the tail of a bird, such as a peacock.

It is primarily within the contemplation of my invention to provide a dancer's personal prop having bird-tail characteristics and capable of being readily and easily manipulated by the dancer for creating original aesthetic terpsichorean effects. And in this aspect of my invention it is an important object to enable the actuating portion of the device to be conveniently carried by the dancer and so positioned upon her as to be unexposed to view.

It is another object of this invention to enable expansible fan-like bird-tails of various designs to be detachably secured to and operatively associated with my invention.

Another object of my invention is to enable the particular bird-tail employed with my invention to be, at the will of the dancer, movably actuated from a horizontal to a vertical position in either expanded or contracted condition. And in this aspect of my invention it is a further object to enable the tail to be held locked in either of said positions so as to enable the dancer to go through certain predetermined steps without displacing the fan from its set position.

It is within the further contemplation of this invention to enable the device to be manipulated, both manually and by certain bodily movements, so as to bring the tail into various predetermined positions either in its contracted, fully expanded or partially expanded conditions, in either horizontal, vertical or intermediate positions.

It is another object of this invention to provide a device of this category with balancing means of such a nature as to enable the tail to be delicately supported in any position, whereby any movement of the dancer will cause the tail to be raised or lowered by the action of the air thereagainst.

Another object of this invention is to enable the tail-supporting member to be firmly and quickly attached, and readily detached, from the body of the dancer.

Other objects, features and advantages will appear from the drawings and description hereinafter given.

Referring to the drawings.

Figure 1 is a side elevation showing the invention applied to the body of a dancer, the dot-dash lines indicating several possible positions of the bird-tail.

Figure 2 is a plan view of the device of Figure 1, showing the tail partially spread.

Figure 3 is an enlarged fragmentary vertical section of a portion of the tail-supporting member, and of a portion of the tail, showing a pocket thereof disposed over one of the radial tail-ribs.

Figure 4 is an enlarged side elevation of the device of my invention shown in its locked position with the tail portion horizontally disposed, 10 the dot-dash lines showing the tail-supporting member in another position.

Figure 5 is a front view of the device of Figure 4.

Figure 6 is a plan view of the device of Figure 4.

Figure 7 is a rear view of the device of Figure 4.

Figure 8 is a fragmentary side view of the releasable retaining means for the retracting elastic, shown in its supporting position.

Figure 9 is a fragmentary rear view of the device of Figure 8.

Figure 10 is a perspective of the corset worn by the dancer and upon which the device is adapted 25 to be supported.

Figure 11 is a bottom view of the device of my invention in the position of Figure 6.

Figure 12 is a bottom view of the left latch for holding the tail-support in its horizontal position, the latch being shown in its released position.

Figure 13 is a front view of the bird-tail in its vertical and expanded position, shown in relation to the dancer.

Figure 14 is a rear view of the device of my invention with the left latch released and the tail member in its vertical position.

Figure 15 is a plan view of the device with 40 both latches released and the tail-supporting member held down in its horizontal position by the weight of the tail feathers.

The preferred form of my invention as illustrated in the drawings contains a vertical and preferably stationary support or back rest 20 45 adapted to be positioned and supported upon the back of the dancer in a manner to be hereinafter described. Pivotedly secured to the lower portion of support 20 at pivot 21 is the movable tail-supporting member 22 adapted to detachably support the tail 23. The said support 20 is supported by the corset 24 suitably reinforced with ribs 25 and containing a brace 26 provided with two hooks 27. The support 20 is hung upon the said hooks 27, through the apertures 28—the support further containing the cushions or pads

29 and 30 adapted to rest against the back and buttocks of the dancer, respectively. The support is firmly held in place upon the hooks by the spring latches 32; and by releasing such latches, the support and appurtenances can be readily removed.

In the form of my invention illustrated, the tail support 22 consists of two spaced parallel plates 31 and 32, respectively; and pivotally mounted on pins 33 connecting said plates are tubular socket retainers 34 the outer terminal ends 35 of which are open to receive the tail ribs 36. These ribs are frictionally retained within the sockets 34, and extend outwardly therefrom in the manner illustrated in Figures 2 and 13.

The tail proper 23 is shown as being of web-like structure, the webs 37 being of limp or flexible material. The tail also contains a plurality of tubular members or pockets 38 extending radially and longitudinally thereof and disposed at the lateral edges of the tail and between the said webs thereof. The pockets 38 are adapted to be slipped over the said ribs 36, whereupon the entire tail 23 may be supported by the ribs which in turn are supported by the sockets or retaining members 34 of member 22. To hold the tail 23 against detachment, hooks 39 are provided adapted to be releasably anchored upon securing elements such as ring 40 attached to member 22 (Figure 3).

The socket members 34 are, as aforesaid, pivotally mounted, whereby they may be moved in arcuate paths along a plane parallel to and between the plates 31 and 32. The said sockets 34 are preferably so disposed as to extend rearwardly in radial directions, so that upon an operative arcuate movement of the said sockets, the tail will be accordingly expanded or contracted. It is also apparent that if the extreme lateral or end sockets 41 are operatively moved outwardly, the other intermediate sockets will be correspondingly moved along arcuate paths, in view of the fact that the connecting webs 37 and the pockets 38 constitute a unitary structure whereby a movement of one of the ribs 36 will be transmitted to the other ribs.

Affixed to the support 20 are the two horizontally disposed brackets 42 each carrying a stop pin 43 adapted to extend through the apertures 44 and 45 in the plates 31 and 32, respectively, when member 22 is in its lowered horizontal position. When the socket members 34 are operatively brought between the said apertures and tail-supporting member 22 is lowered, the sockets will be confined between the stops 43 and the tail 23 will accordingly be maintained in its contracted condition. When the member 22 is raised, the sockets will obviously be free to move outwardly and the tail expanded. It is to be further noted, however, that if any of the socket members 34 should be disposed laterally beyond the stops 43, the tail will be correspondingly in expanded condition even when the member 22 is down.

The tail-supporting member 22 has attached thereto a pair of releasable resilient members or elastics 47, the lower portions being preferably permanently affixed to hooks 48 and the upper portions detachably secured to the hooked end portions 49 of shaft 50 rotatively mounted within bearing members 51 secured to the top of member 20. The said hooked ends 49 hold the elastics 47 against detachment while in their upturned position; but when they are operatively rotated

forwardly to a downwardly extending position, the elastics become automatically detached—all in a manner to be more fully hereinafter described. The said elastics 47, when in their attached positions, urge the member 22 upwardly to its vertical or retracted position. This upward action is augmented by the spring 52 which also urges member 22 upwardly.

Pivotedly mounted upon the support 20 is the flap member 53 yieldably urged against the upper plate 31 of member 22 by spring 54, the flap being held in its upright retracted position against support 20 by the releasable latch member 55 to be hereinafter described. It is preferred that springs 52 and 54 be of such resilient properties as to practically counterbalance each other—although it is to be understood that the tension of these springs may, if necessary, be varied in accordance with the weight of tail 23 or other factors which might tend to unbalance the structure. When the elastic members 47 are operatively detached, in the manner to be hereinafter described, the member 22 will, under the influence of the weight of the tail 23, be lowered until it assumes a horizontal position, the dancer being able to retard the downward pivotal movement of said member 22 by a rearward movement so as to enable the air to provide a slightly upward lift against the underside of the tail. Where the particular tail employed happens to be too heavy to permit a gradual downward movement of said member 22, one or more supplementary elastics 56 anchored between members 20 and 22 may be employed whereby the upward pull of such elastics partially off-sets the gravitational effect upon the tail.

The tail-holding member 22 is releasably held in its horizontal position by latch member 57 which, in the form thereof illustrated, is rotatively mounted on shaft 58 supported by bracket 59. The underside of member 57 is provided with a curved surface 60 engaging the lower plate 32. Inasmuch as the member 22 is normally urged upwardly as aforesaid, said lower plate 32 would, in engaging said surface 60, cause it to rotate horizontally about its axis, and thereby be retracted from its locking position. In order to maintain the latch 57 in its locking position, the locking element 61, pivotally mounted on shaft 62, is manually swung into pressing engagement with the rear of latch member 57, thereby frictionally holding it in its projected locking position. To effect an unlocking thereof, the string 63 is pulled by the dancer, thereby causing a rotational movement of lock 61, whereupon the latch 57 is forced into its retracted position by plate 32 which moves upwardly under the influence of the elastic members 47 and the other yieldable members operatively associated therewith, as aforesaid.

A similar locking arrangement holds flap 53 against plate 20, the latch member 55 being frictionally held in its projected position by the pivotally mounted lock 64. When the dancer pulls string 65, the lock 64 is rotatively moved out of engagement with latch 55 which is accordingly rotatively retracted by the downward movement of flap 53 under the influence of spring 54.

It will be observed that the said flap 53 has attached thereto the cable 66 which is attached to pulley 67 at 68. When the flap 53 is in its vertical or locked position, the shaft 58, upon which pulley 67 is fixedly mounted, is in such position that the hooks 49 are upwardly disposed, so that the elastic members 47 are held

thereupon by the links 68. However, when the flap 53 is released by latch 55, its downward movement will carry with it the said cable 66, thereby causing the pulley 67 to rotate and produce a corresponding rotation of shaft 50 until the hooks 49 are downwardly disposed. In this position, the links 68 will become disengaged from hooks 49, and the elastics 47 will consequently become disconnected from the support 28, whereupon it will no longer tend to urge member 22 upwardly.

The tubular socket retainers 34 are partially controlled by a pulley system comprising two cables 70 and 71, pulleys 72, 73, 74, 75, 76 and 77. The said cables 70 and 71 are connected at the rear of member 20 by a link member 78 to a member 79 suspended from support 20 at 80; and the forward terminals of said two cables 70 and 71 are connected to the end sockets 41 as clearly shown in Figures 6 and 11. In the structure shown, the cables pass through apertures 83 and 84 of plate 32 in connecting up with the various pulleys. When the member 22 is operatively moved downwardly, the forward portions of cables 70 and 71 will be correspondingly carried upwardly a short distance, thereby causing an outward movement of the tubular sockets 41 and a consequent spreading and expansion of the entire tail. The resilient member 79 aids in producing a safe and effective pull upon said end sockets 41, its action being indicated in Figure 5.

In operatively employing this device, the corset 24 is firmly affixed to the dancer in conventional manner, and the apparatus placed upon the hooks 27 as aforesaid. The dancer is obviously supplied with plumage or other drapes to completely hide the mechanism. In the initial setting of the device, the tail-holding member 22 is brought down to its horizontal position, and maintained in such position by means of the latch member 57. The pressing member 53 is brought into its vertical position and maintained therein by latch member 55. The elastic members 47 are placed upon shaft 50 and the shaft rotated until the hook members 49 are in their upper position as indicated in Figures 8 and 9. It should be noted that the pulley 67 is held releasably locked in such position by spring detent 81 bearing up against a co-acting recess in the pulley—the detent being capable only of holding the pulley in its retracted position when the flap 53 is raised. In starting it is preferred, although not absolutely essential, that the socket members 34 and associated tail be in their respective contracted positions between stop pins 43. Inasmuch as the tail is horizontally disposed, it is obvious that the dancer will be able to make her entrance upon the stage through the wings without difficulty. The dancer may hold the two strings 63 and 65 in both hands upon entering the stage, or she may later grasp them for suitable manipulation.

With the device set as above described, the dancer is free to go through her terpsichorean gyrations without encumbrance, and is likewise capable of manually spreading or contracting the tail within the physical limitations of the structure. The skilled dancer, experienced in the operative use of this device, can by suitable hip movements cause the tail by its own inertia or momentum to spread or contract, this action being aided by suitable manual manipulation to produce beautiful aesthetic results.

To bring the tail to a vertical position, the dancer pulls string 63, as aforesaid, whereupon member 22 will be urged upwardly under the in-

fluence of elastics 47 and spring 52. This upward movement, however, is retarded by the weight of the tail, and can be further retarded by a slightly forward movement of the dancer whereupon the wind pressure upon the upper surface of the tail will produce a counter-balancing effect. When the tail is in the upper position, the end socket members 41 will be pulled outwardly by the pulley system above described, thereby causing a spreading of the tail somewhat in the manner illustrated in Figure 13. It is to be observed that the retardation of the downward spreading movement of the socket members 34 can be accomplished by the action of the air against the webs of the tail upon a proper forward or rearward movement of the dancer. In this position the dancer can go through her steps to produce further pleasing effects with the tail in its fully expanded and upright position.

The tail will remain in a vertical position until the dancer pulls string 65, whereupon the latch 55 is retracted and flap 53 released. When this occurs, the said flap 53, under the influence of spring 54, will press down upon upper plate 32 thereby counter-balancing the action of spring 52 tending to urge the member 22 into its upward position. It will be observed that when flap 53 is moved downwardly, the hooks 49, in the manner above described, will be turned downwardly to enable the elastics 47 to become disengaged, so that only the said spring 52 tends to urge the member 22 upwardly. It is thus apparent that in this condition the entire member 22 may be delicately balanced; and it is preferred that the tail and balancing mechanism be so adjusted that the tail will gradually assume a horizontal position, moving downwardly under the influence of the weight of the tail 23. As above indicated, if it is found that the particular tail employed is too heavy for this effect, the elastic means 56 may be employed to retard the drop—the downward movement being capable of further retardation by a rearward movement of the dancer, in the manner above described.

When the apparatus is in this balanced condition, the dancer will be readily able to raise or lower the tail either manually, or by wind pressure upon forward and rearward movements during the course of her dance. Various aesthetic effects can thus be produced with the apparatus in this position. It will further be observed that the dancer will be able to make her exit when both latches are in released condition, inasmuch as the tail can be disposed horizontally and contracted so as to enable egress through an exit of restricted proportions.

It is of course understood that the embodiment of my invention above described and shown in the drawings is merely illustrative of my invention, and that numerous changes and modifications may be made therein within the scope of the appended claims without departing from the spirit of this invention.

What I claim is:

1. In a dancer's device of the class described, a substantially vertical support adapted for attachment against the back of the dancer, a tail member pivotally attached to the support and movable between substantially vertical and horizontal limiting positions, releasable yieldable means urging said member upwardly to said vertical position, releasable yieldable means urging said member downwardly to said horizontal posi-

tion, and releasable latch means for holding said member locked in either of said positions.

2. In a dancer's device of the class described, a substantially vertical support adapted for attachment against the back of the dancer, a tail holding member pivotally attached to the support and movable between substantially vertical and horizontal limiting positions, releasable yieldable means urging said member upwardly to said vertical position, releasable yieldable means urging said member downwardly to said horizontal position, a tail attached to said holding member urging the member downwardly under the influence of its weight, resilient balancing means urging the said member upwardly against the action of said tail, and means for releasably holding said member locked in either of said limiting positions.

3. In a dancer's device of the class described, a substantially vertical support adapted for attachment against the back of the dancer, a tail holding member pivotally attached to the support and movable between substantially vertical and horizontal limiting positions, a tail attached to said holding member urging the member downwardly under the influence of its weight, and resilient balancing means urging the said member upwardly against the action of said tail, said tail containing web-like portions, whereby upon a forward or rearward movement of the dancer the tail will be raised or lowered by the pressure of the air against the webs in opposition to the weight of the tail and the action of said balancing means, respectively.

4. In a dancer's device of the class described, a substantially vertical support adapted for attachment against the back of the dancer, a pad member secured to the support and adapted for abutment against the dancer's back, and an expandable tail member mounted upon said support, said member containing a plurality of radial rib members the inner portions of which are pivotally mounted and movable along arcuate paths, said rib members being joined by connecting members, whereby the tail will expand or contract in fan-like manner upon being actuated by the bodily movements of the dancer transmitted through said pad member and support.

5. In a dancer's device of the class described, a substantially vertical support adapted for attachment to the body of the dancer, an expandable tail member pivotally attached to the support and movable between substantially vertical and horizontal limiting positions, said member containing a plurality of radial rib members the inner portions of which are pivotally mounted and movable along arcuate paths to permit an operative expansion and contraction of the tail member, a plurality of stops secured to said support and extending between said rib members when the tail member is in its horizontal position, whereby the path of certain of said rib members will be intercepted and the rib members prevented from movement therebeyond.

6. In a dancer's device of the class described, a substantially vertical support adapted for attachment to the body of the dancer, an expandable tail member pivotally attached to the support and movable between substantially vertical and horizontal limiting positions, said member containing a plurality of radial rib members the inner portions of which are pivotally mounted and movable along arcuate paths, said rib members being joined by connecting members, and cable means secured at one end to the sup-

port and at the other end to at least one of the two laterally extreme rib members, whereby upon an upward movement of the tail member the said extreme rib members will be pulled outwardly by the cable means and the tail accordingly expanded.

7. In a dancer's device of the class described, a substantially vertical support adapted for attachment to the body of the dancer, a tail holding member pivotally attached to the support and movable between substantially vertical and horizontal limiting positions, a plurality of tubular sockets pivotally mounted upon said member, and a tail comprising a plurality of ribs and connecting webs of limp material, the innermost portions of said ribs being in frictional engagement with and supported by said sockets, whereby upon an operative pivotal movement of the sockets the tail will correspondingly expand or contract.

8. In a dancer's device of the class described, a substantially vertical support adapted for attachment to the body of the dancer, a tail member pivotally attached to the support and movable between substantially vertical and horizontal limiting positions, resilient means urging said member upwardly towards its vertical position, a pivotally mounted pressing member secured to said support and adapted for downward pressing engagement with said tail member, yieldable means urging said pressing member against said tail member towards its said horizontal position, and releasable locking means for holding said tail member in its horizontal position and said pressing member out of pressing engagement with the tail member, respectively.

9. In a dancer's device of the class described, a substantially vertical support adapted for attachment to the body of the dancer, a tail member pivotally attached to the support and movable between substantially vertical and horizontal limiting positions, resilient means urging said member upwardly towards its vertical position, a pivotally mounted pressing member secured to said support and adapted for downward pressing engagement with said tail member, yieldable means urging said pressing member against said tail member towards its said horizontal position, and releasable latch members associated with said tail and said pressing members for holding the former in its horizontal position and the latter out of engagement with the tail member, said latch members each comprising a retractile latch, a movable lock member for frictionally holding the latch in locking position, and manual means manipulable by the dancer for operatively disengaging the lock from the latch to permit its retraction.

10. In a dancer's device of the class described, a substantially vertical support adapted for attachment to the body of the dancer, a tail member pivotally attached to the support and movable between substantially vertical and horizontal limiting positions, resilient means urging said member upwardly towards its vertical position, yieldable means urging said tail member downwardly towards its horizontal position, said resilient means including a detachable resilient element connecting the said support to said tail member, and releasable anchoring means for detachably holding said resilient element.

11. In a dancer's device of the class described, a substantially vertical support adapted for attachment to the body of the dancer, a tail member pivotally attached to the support and mov-

able between substantially vertical and horizontal limiting positions, resilient means urging said member upwardly towards its vertical position, a pivotally mounted pressing member secured to said support and adapted for downward pressing engagement with said tail member, yieldable means urging said pressing member against said tail member towards its said horizontal position, releasable locking means for holding said tail member in its horizontal position and said pressing member out of pressing engagement with the tail member, respectively, the said resilient means including a detachable resilient element connecting the said support to said tail member, and releasable anchoring means for detachably holding said resilient element, said anchoring means being movably mounted upon the support and connected to said pressing member, whereby upon an operative release of the pressing member the anchoring means will be movably actuated to release the said resilient element.

12. In a dancer's device of the class described, a substantially vertical support adapted for attachment to the body of the dancer, a tail member pivotally attached to the support and movable between substantially vertical and horizontal limiting positions, resilient means urging said member upwardly towards its vertical position, a pivotally mounted pressing member secured to said support and adapted for downward pressing engagement with said tail member, yieldable means urging said pressing member against said tail member towards its said horizontal position, releasable locking means for holding said tail member in its horizontal position and said pressing member out of pressing engagement with the tail member, respectively, the said resilient means including a detachable resilient element connecting the said support to said tail member, and releasable anchoring means for detachably holding said resilient element, said anchoring means including a shaft rotatably mounted on the support, hooked means on the shaft detachably supporting said resilient element, a pulley affixed to the shaft, and a cable extending from the pulley to said pressing member, whereby upon an operative release of the pressing member the said cable will be carried downwardly to operatively rotate the shaft and release the resilient element from the said hooked means.

13. In a dancer's device of the class described, a substantially vertical support adapted for attachment against the back of the dancer, a tail holding member containing a substantially flat plate pivotally attached to the support and movable between substantially vertical and horizontal limiting positions, a plurality of rib-retaining members pivotally attached to the plate and movable in arcuate paths in a plane parallel to the plate, a tail comprising a plurality of ribs and connecting web portions, the ribs being in frictional engagement with and supported by said retaining members, said plate having an apertured portion adjacent the said retaining members, and an upstanding pin stop secured to said support and extending upwardly through said apertured portion of the plate when in its horizontal position and in intercepting relation to the path of travel of the retaining members.

14. In a dancer's device of the class described, a substantially vertical support adapted for attachment against the back of the dancer, a tail holding member containing a substantially flat plate pivotally attached to the support and movable between substantially vertical and horizontal limiting positions, a plurality of rib retaining members pivotally attached to the plate and movable in arcuate paths in a plane parallel to the plate, a tail comprising a plurality of ribs and connecting web portions, the ribs being in frictional engagement with and supported by said retaining members, said plate having an apertured portion adjacent the said retaining members, a resilient member attached to the support, pulley means associated with the support and the plate, and cable means coacting with said pulley means and connecting said resilient member with the two opposite and laterally extreme retaining members, whereby upon an upward movement of the said plate the said retaining members will be pulled outwardly by the cable means and the tail accordingly expanded.

15. In a dancer's device of the class described, a substantially vertical support adapted for attachment against the back of the dancer, a tail holding member containing two spaced parallel flat plates pivotally attached to the support and movable between substantially vertical and horizontal limiting positions, a plurality of rib-retaining members disposed between the plates and pivotally attached to and movable in arcuate paths between the plates, a tail comprising a plurality of ribs and connecting web portions, the ribs being in frictional engagement with and supported by said retaining members, a resilient member attached to the support, pulley means associated with the support and the plates, and cable means coacting with said pulley means and connecting said resilient member with the two opposite and laterally extreme retaining members, whereby upon an upward movement of the said plates the said retaining members will be pulled outwardly by the cable means and the tail accordingly expanded.

16. In a dancer's device of the class described, a substantially vertical support adapted for attachment against the back of the dancer, a tail holding member containing two spaced parallel flat plates pivotally attached to the support and movable between substantially vertical and horizontal limiting positions, a plurality of rib-retaining members disposed between the plates and pivotally attached to and movable in arcuate paths between the plates, a tail comprising a plurality of ribs and connecting web portions, the ribs being in frictional engagement with and supported by said retaining members, one of said plates having an apertured portion, a resilient member attached to the support, a plurality of pulleys attached to the support and the plates, and cable means extending from said resilient member, over said pulleys, through said apertured portion to the two opposite and laterally extreme retaining members, whereby upon an upward movement of the said plates the said retained members will be pulled outwardly by the cable means and the tail accordingly expanded.
